Des. 1831

Charles Ledaird, of Brooklyn, N.Y.
Letters Patent No 1831 dated Oct 18th 1863.

Design for a Bottle.

The schedule referred to in these Letters Patent and making part of the same.

To all whom it may concern:

Be it known that I, Charles Ledaird, of the City of Brooklyn, in the County of Kings and State of New York, have invented a new Design for a Bottle; and I do hereby declare that the following is a full, clear and exact description of the same, reference being had to the accompanying drawings, forming part of this specification, in which,

Figures 1 and 2 are elevations of two different sides of the bottle.

Figure 3. is a horizontal section of the same.

in the plane indicated by the line x.x, of figure 1.

Similar letters of reference indicate corresponding parts in the several figures.

The general design of the bottle is that of a three-sided house with a high pitched roof and with a chimney in the centre, the chimney being formed by the neck and mouth of the bottle. The corners, both of the sides and roof are flattened, as shown at a.a, in figure 3, and finished off towards the sides of the bottle in the form of beads b.b, which are continued around the bottom, as shown at c.c, and along the junction between the sides and the shoulders of the bottle which represent the roof, as shown at d.d. Two sides are corrugated, as shown at e.e, in figures 1 and 3, to represent upright unsquared logs, and the third side is flat, as shown at f, and g, in figures 2 and 3, to represent the door of the house, and a window, the door f, and window g, above, being separated by the bead d'. Upon the upper flat part g, representing the window, are formed in raised letters the inscription OK PLANTATION 1840.

The portions of the beads b.b, running up each side of the shoulder of the bottle are united in the form of arches, as shown at h.h. The base of the chimney like neck is finished off in the form of a cyma-recta, as shown at i.i.

What I claim, and desire to secure by Letters Patent, is,

The design and configuration of the three-sided bottle, as herein described and represented in the accompanying drawings.
